Primary Examiner — Steven J Czyz

CLAIM

The ornamental design for an electronic pill box, as shown and described.

DESCRIPTION

FIG. 1 is a top perspective view of an electric pill box showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the electronic pill box, shown in use connected to other pill boxes.
The broken lines in the drawings depict portions of the electronic pill box that form no part of the claimed design.

1 Claim, 9 Drawing Sheets
